United States Patent Office

Des. 188,683

Patented Aug. 23, 1960

188,683

PLATE OR SIMILAR ARTICLE

John H. Reiser, Downey, Calif., assignor to Wallace China Co. Ltd., Los Angeles, Calif., a corporation of California

Filed Mar. 7, 1960, Ser. No. 59,644

Term of patent 3½ years

(Cl. D44—15)

The figure is a plan view of a plate of conventional configuration showing my new design.

The section of motif shown is continued around the entire circumference of the plate.

I claim:

The ornamental design for a plate or similar article, substantially as shown and described.
